UNITED STATES PATENT OFFICE

2,529,665

FLOATLESS CARBURETOR

Andrew Craig Russell, Shawnee, Okla.

Application May 12, 1947, Serial No. 747,409

1 Claim. (Cl. 261—50)

1
This invention relates to devices in the nature of a carburetor for internal combustion engines and has for its primary aim the provision of a fuel mixing apparatus that is entirely automatic in its operation and devoid of the fuel chamber float present in common types of carburetors.

The most important object of this invention is to provide a carburetor similar in many respects to that disclosed in my previous issued U. S. Letters Patent No. 2,366,056, dated December 26, 1944, and to improve upon the carburetors shown in my co-pending applications Serial Numbers 646,767, 691,944 and 710,519, dated February 11, 1946, August 21, 1946 and November 18, 1946, respectively. This is a continuation in part of said applications.

Another important object of this invention is the provision of a carburetor having a fuel bowl provided with an inlet connected with a source of fuel supply and an overflow pipe for carrying excess fuel back to the source of supply to the end that a continuous flow is present when the carburetor is operating at less than full capacity.

A further object of this invention is to provide a carburetor having the aforesaid means for supplying fuel thereto and a valve assembly operable entirely by the extent of air flow through the carburetor.

A still further object of this invention is to provide a floatless carburetor for internal combustion engines having a tubular member interconnecting the carburetor housing and the fuel bowl and provided with a plurality of passages for introducing air from the interior of the housing to the level of fuel within the tubular member.

Another object of this invention is to provide a carburetor of the aforementioned type having a collar within the housing in circumscribing screw-threaded engagement with the tubular member and having a portion surrounding and in spaced relation to the outlet ends of the aforesaid passages, all to the end that air may enter the tubular member and mixing chamber therein at all times in an even, steady flow.

Many minor objects of this invention will be made clear or become apparent during the course of the following specification, reference being had to the accompanying drawing, wherein:

Fig. 1 is a vertical substantially central sectional view through a floatless carburetor made in accordance with my present invention; and

Fig. 2 is a cross sectional view taken on line II—II of Fig. 1, looking in the direction of the arrows.

A hollow housing broadly designated by the **55**

2
numeral 10 is sectional and when assembled, presents an air intake 12, and an air outlet 14 which is in communication with a pipe not shown, leading to the intake manifold of the internal combustion engine in the usual manner.

The pipe which interconnects the carburetor and the internal combustion engine is provided with a conventional butterfly valve having connection with an operating lever for controlling the speed of the engine, all of which is not shown in the drawing and may be formed in any of the conventional manners similar to that disclosed in my U. S. Letters Patent No. 2,366,056. The air intake passage 12 is equipped with a butterfly valve 16 to control the amount of air entering the carburetor.

A fuel bowl 18 forms a part of the housing 10 and depends from the normally lowermost wall 20 thereof. This fuel bowl 18 may be detachably secured to the housing 10 in any suitable manner to present a hermetically sealed chamber for receiving the fluid from a source of supply.

The fuel bowl 18 may be drained if desired, by removing a plug 22 disposed in the normally lowermost wall of fuel bowl 18. An elongated tubular member 24 disposed within the fuel bowl 18 passes through an opening formed in the wall 20 of housing 10 and extends upwardly into the continuous air passage through housing 10 which interconnects intake 12 and air outlet 14. This tubular member 24 is provided with a pair of spaced apart substantially parallel plates 26 and 28 for purposes hereinafter more fully described and the plate 26 underlies and is secured to the wall 20 through the medium of screws or the like, not shown. The normally uppermost end of this tubular member 24, or that portion thereof which extends into the housing 10, is externally threaded as at 30 to receive an internally threaded collar 32. The threads 34 of this collar 32 are in mesh with the threads 36 of member 24 to the end that rotation of the collar 32 moves the lowermost end thereof toward and away from the innermost face of the bottom wall 20 of housing 10.

This collar 32 is provided with a plurality of longitudinal ribs 38 and a screw 38 is threaded into a threaded bore 40 formed in one wall 42 of housing 10. This screw 38 extends into the housing 10 and is in contacting relationship with the collar 32 when the screw 38 is in the operative position. When the innermost end of screw 38 is in engagement with collar 32, the ribs 38 prevent rotation of collar 32 with respect to the tubular member 24. When the collar 32 is set in the desired position, a lock nut 44 on the screw 38

and disposed exteriorly of housing 10, holds screw 38 in the operative position.

A pair of spaced apart substantially parallel posts 46 are slidably mounted within openings 48, 50 and 52 in wall 26, plate 26 and plate 28 respectively. A disc 54 disposed within the fuel bowl 18 joins the lowermost ends of the posts 46 and the uppermost ends of these posts 46 are joined by a closure 56 mounted within the passageway through housing 10 joining intake 12 and outlet 14. This closure member 56 rests upon the collar 32 and cooperates therewith in substantially closing the passageway through housing 10 when the assembly, including posts 46, is at the lowermost end of its path of travel as illustrated in Figs. 1 and 2. A longitudinal bore 58 is formed within the member 24 and has press-fitted or otherwise affixed thereto a pipe 60 at its normally uppermost end and this pipe 60 terminates within the housing 10 in spaced relation to the closure 56 and the collar 32. The other end of the bore 58 has a tubular plug 62 threaded therein for slidably receiving a tapered valve 64. This valve 64 substantially closes the opening through the plug 62 when the plate 54 is at the lowermost end of its path of travel. The valve 64 rests upon the disc 54 joining the posts 46 and is actuated by the vertical reciprocating movement of posts 46, disc 54 and closure member 56.

The longitudinal bore 58 formed in the member 24 is of reduced diameter intermediate the ends thereof to present a restricted passage 66. A plurality of passages 68 extend downwardly and inwardly from housing 10 to interconnect the latter with the interior of bore 58. These passages 68 terminate at their inner ends above, and in spaced relation to the passage 66, and above the level of fuel within the bowl 18 and within the bore 58. The passage 66 serves to maintain said level of fuel within bore 58 below the inner end of passages 68.

The normally lowermost end of the collar 32 is provided with a cavity 70 of greater diameter than the threaded bore 34 thereof and this cavity 70 is in circumscribing spaced relationship to the normally uppermost and outermost ends of the passages 68, as clearly illustrated in Fig. 1 of the drawing.

The operation of the valve 64 is similar to that disclosed in my aforesaid U. S. Letters Patent. This constitutes essentially an opening and closing of the valve 64 by longitudinal reciprocation thereof within the bore 58 through actuation of the disc 54. As a greater or lesser amount of fuel mixture is allowed to pass into the internal combustion engine through the operation of the butterfly valve between the carburetor and the manifold as above described, air passing through the housing 10 from inlet 12 into the air outlet 14, will raise and lower the member 56 from the collar 32, permitting such air to pass upwardly around collar 32 to mix with the mixture emanating from the uppermost end of the pipe 60. During operation of the internal combustion engine, air is free to flow into the bore 58 through the passages 68 except during choking when the butterfly valve 16 is moved to a position to present a richer mixture.

As set forth in my U. S. Letters Patent No. 2,366,056, there is a level of fuel within the bore 58 below the innermost ends of the passages 68, and as air enters bore 58 it strikes the shoulder therein, produced by the reduced passage 66 thereof and creates a turbulence. This turbulent air acts upon the level of fuel in bore 58, and the

5 mixture is moved toward the outlet end of pipe 60 by suction in the engine.

6 Collar 32 prevents a direct flow of air from the housing 10 into the bore 58, the passage being somewhat circuitous and, therefore, equalized pressure is attained before entrance of the air into bore 58.

7 It is through use of the assembly just described that it is possible to eliminate the usual type of float within the fuel bowl 18. In lieu thereof, this carburetor is provided with an inlet opening 72 for receiving a conduit 74 having connection with the usual type of fuel pump not shown, which receives fuel from a source of supply in the usual manner. A fitting 76 communicating with the fuel bowl 18 below the intake opening 72 has connection with an overflow pipe 78. This overflow pipe has the opposite end thereof connected to the conduit which joins the fuel pump of the internal combustion engine with the fuel tank. When the engine is idling and the fuel pump is operating, a continuous flow of fuel passes from the fuel pump through the conduit 74 into the opening 72 and finally into the fuel bowl 18. The carburetor, during such idling operation of the engine, uses only a small amount of the full capacity of the fuel pump and the conduit 74 and such excess overflows into the pipe 78 and empties back into the pipe interconnecting the fuel pump and the fuel tank. As the amount of fuel being used by the internal combustion engine is increased through the operation of the carburetor just above described, the extent of overflow of fuel into the pipe 78 progressively decreases. Obviously, the total capacity of the conduit 74 is greater than the total capacity of the overflow pipe 78 and by the same token, when the carburetor is operating at full capacity, the capacity of the conduit 74 is such as to maintain a level of fuel in bowl 18 substantially as shown in Figs. 1 and 2. In other words, as the greatest amount of fuel which may pass through the bore 58 of member 24 is reached, the extent of overflow of fuel from the pipe 78, decreases. It is seen, therefore, that during operation of the carburetor, the fuel bowl 18 always contains enough fuel to supply bore 58, 66 and as the valve 64 is moved toward the closed position, an increasing amount of fuel will overflow into the pipe 78. Thus the level of fuel in bowl 18 will vary slightly during operation, particularly during rapid acceleration changes, but will never raise or drop to a great extent with respect to overflow pipe 78.

8 Formation of the carburetor as just described, eliminates many unnecessary parts which decreases the cost of production substantially and provides for a more efficient operating carburetor generally.

9 The elimination of means for actuating the collar 32 as provided in my aforesaid U. S. Letters Patent, as well as omission of the float within the fuel bowl 18, obviates the need of a multitude of parts that would otherwise tend to cause trouble because of maladjustment and other operating defects. Furthermore, it has been found that the carburetor as herein disclosed, operates as efficiently with these parts eliminated and has the same advantages with respect to economy and excellence of performance as the carburetor forming the subject matter of my aforesaid patent. In addition, the improvements herein set forth increases economy of operation, decreases initial cost of production of the carburetor and enhances smooth operation.

Manifestly, many modifications and changes may be made, particularly in details of construction, without departing from the spirit of the invention or scope of the appended claims.

Having thus described the invention, what is claimed as new and desired to be secured by Letters Patent is:

In a carburetor for internal combustion engines having a housing, a continuous air passage through the housing, a fuel bowl depending from one wall of the housing, a tubular member in the fuel bowl and extending into the housing through said one wall thereof, said tubular member having a mixing chamber formed therein and a plurality of passages disposed to direct air from the housing into said mixing chamber and thence downwardly against the surface of fuel therein, the improvement of which includes a collar having an outturned flange at the upper end thereof and a plurality of grooves formed on the periphery of the collar below said flange, said grooves being parallel to the axis of rotation of the collar, a portion of the collar being in circumscribing relationship with the tubular member adjacent the outermost ends of said passages

25

and spaced therefrom; a movable annular valve in the passage and resting on said flange when at one end of its path of travel; a second valve operably joined to the first valve for controlling the flow of fuel from the bowl to the mixing chamber, said collar being threadably mounted on the tubular member for adjusting the position of the valves at said one end of the path of travel; and a set screw threadably mounted in the housing for engagement with said grooves whereby said collar is releasably held from movement out of adjustment.
